UNITED STATES PATENT OFFICE.

RANSOM Y. BOVEE, OF BLOOMINGTON, ILLINOIS.

WRENCH.

1,240,171.

Specification of Letters Patent. Patented Sept. 18, 1917.

Application filed May 28, 1915, Serial No. 30,959. Renewed February 12, 1917. Serial No. 148,258.

To all whom it may concern:

Be it known that I, RANSOM Y. BOVEE, a citizen of the United States, residing at Bloomington, in the county of McLean and State of Illinois, have invented a certain new and useful Improvement in Wrenches, of which the following is a specification.

My invention relates to improvements in wrenches, particularly so-called pipe wrenches. It has for one object to provide a wrench in which the distance between the two jaws may be easily and conveniently adjusted to take any size of pipe in which the wrench may be manipulated with one hand adjustment being made with the thumb of the operator.

Another object is to provide a wrench which will be rigid and durable in which side thrusts or twisting of the wrench may occur without distorting it. Other objects of my invention will appear in the specification.

Figure 1 is a side elevation;

Fig. 2 a plan section with parts broken away;

Fig. 3 a side elevation in a different position in part section with parts broken away.

Like parts are indicated by the same letters in all the figures.

A is the wrench handle, A¹ the wrench head made up of two parallel side walls A², A³ joined at the bottom by a transverse wall A⁴. From these walls rises upwardly a housing A⁵, the two sides of which project upwardly one from each of the walls A², A³ and are tied together by a fixed yoke A⁶ across the top, which yoke has an inner concave surface A⁷. A⁸ is a toothed, fixed, though removable, pipe contacting jaw mounted on the head A¹.

Extending transversely across the lower side of the head is a cylindrical pivot bearing B cut away at one side. In it is rotatably mounted a pivot B¹. This pivot carries the rocking yoke B² slotted as indicated having a curved surface B³ adapted at one end of its movement to engage the surface A⁷, the upper extremity of the rocking yoke being provided with a tooth carrying lug B⁴ projecting forwardly therefrom narrower than the yoke and adapted as indicated in Fig. 1 to pass between the two forward side walls of the part A⁵ when thrust into position by the spring B⁵ engaging a

pin B⁶ on the back of the yoke B² and located within a socket B⁷ in the head A¹.

C is a shank slideable in the yoke B². It is smooth on one side in engagement with the hump C¹ on the yoke B² and toothed at C² to engage the teeth on the lug B⁴. C³ is a thumb-piece on the end of the shank C and C⁴ is a jaw carried thereby in opposition to the jaw A⁸. It will be noted that the end of the shank engages or penetrates the slot between the walls A², A³ and above the wall A⁴.

It will be evident that while I have shown in my drawing an operative device, still many changes might be made in size, shape and arrangement of parts without departing from the spirit of my invention. I wish therefore that my drawing be regarded as in a sense diagrammatic.

The use and operation of my invention are as follows:

The operator holds the wrench in his hand in the usual manner. When he wishes to open the jaws he puts his thumb on the thumb-piece and pulls down and back, rotating the shank and the yoke which carries it from the position shown in Fig. 1 to the position shown in Fig. 3, the downward and rearward pressure being exerted on the hump to cause the yoke to rock away from the teeth. He may then by continuing his pressure downwardly while he draws back or pushes forward as the case may be slide the shank back and forth, it being necessary only that he continue his pressure to hold the yoke in position against the spring. As soon as this pressure is released the spring rotates the yoke and drives it back to the position shown in Fig. 1 to hold the parts together. It will be understood that only a downward and rearward pressure on the thumb-piece will rotate the yoke to free the shank. If pressure is exerted against the nose of the moving jaw it only tends to press the shank up against the toothed portion on the yoke, and although this would simultaneously exert a pressure on the hump the lever arm between the lug and pivot is greater than the lever arm between the hump and pivot, and so the upward pressure resists and overcomes the downward pressure and the teeth are firmly engaged.

Of course, this does not prevent a rearward movement of the shank, but since the

wrench operation tends always to draw the shank out and not to force it in it has an outward movement which must be resisted.

I claim:

- 5 1. A wrench comprising a handle, a hollow head and a jaw carried thereby, a yoke pivotally mounted within the head, a shank extending through and in rotatable and 40 slidable engagement with both head and yoke, a jaw carried thereby in opposition to the jaw on the handle, clamping surfaces on the yoke and means for yieldingly rotating it to bring them into such engagement with opposed sides of the shank that a 45 plane perpendicular to the shank containing the axis of rotation of the yoke lies between the contact areas.
- 10 2. A wrench comprising a handle, a hollow head and a jaw carried thereby, a yoke pivotally mounted within the head, a shank extending through and in rotatable and 50 slidable engagement with both head and yoke, a jaw carried thereby in opposition to the jaw on the handle, clamping surfaces on the yoke and means for yieldingly rotating it to bring them into engagement with opposed sides of the shank.
- 15 3. A wrench comprising a handle, a hollow head and a jaw carried thereby, a yoke pivotally mounted within the head, a shank extending through and in rotatable and 55 slidable engagement with both head and yoke, a jaw carried thereby in opposition to the jaw on the handle, clamping surfaces on the yoke and means for yieldingly rotating it to bring them into engagement with opposed sides of the shank, and means 60 contained within the head for limiting the rotational movement of the yoke.
- 20 4. A wrench comprising a handle, a hollow head and a jaw carried thereby, a yoke pivotally mounted within the head, a shank extending through and in rotatable and 65 slidable engagement with both head and yoke, a jaw carried thereby in opposition to the jaw on the handle, clamping surfaces on the yoke and means for yieldingly rotating it to bring them into engagement with opposed sides of the shank, and means contained within the head for limiting the 70 rotational movement of the shank.
- 25 5. A wrench comprising a handle, a hollow head and a jaw carried thereby, a yoke pivotally mounted within the head, a shank extending through and in rotatable and 75 slidable engagement with both head and yoke, a jaw carried thereby in opposition to the jaw on the handle, clamping surfaces on the yoke and means for yieldingly rotating it to bring them into engagement with opposed sides of the shank, and means contained within the head for limiting the 80 rotational movement of both the shank and the yoke.

opposed sides of the shank, and means contained within the head for limiting the rotational movement of the shank.

4. A wrench comprising a handle, a hollow head and a jaw carried thereby, a yoke pivotally mounted within the head, a shank extending through and in rotatable and 45 slidable engagement with both head and yoke, a jaw carried thereby in opposition to the jaw on the handle, clamping surfaces on the yoke and means for yieldingly rotating it to bring them into engagement with opposed sides of the shank, and means contained within the head for limiting the 50 rotational movement of the yoke.

5. A wrench comprising a handle, a hollow head and a jaw carried thereby, a yoke pivotally mounted within the head, a shank extending through and in rotatable and 55 slidable engagement with both head and yoke, a jaw carried thereby in opposition to the jaw on the handle, clamping surfaces on the yoke and means for yieldingly rotating it to bring them into engagement 60 with opposed sides of the shank, and means contained within the head for limiting the rotational movement of both the shank and the yoke.

In testimony whereof, I affix my signature in the presence of two witnesses this 24th day of May, 1915.

RANSOM Y. BOVEE.
